MEANS FOR GUIDING, FLOATING, AND CEMENTING WELL CASING IN BORED HOLES

Sylvester B. Schnitter, Dallas, Tex., assignor to
L. L. Rector, Tarrant County, Tex.

Application June 27, 1947, Serial No. 757,452

10 Claims. (Cl. 166—1)

1
This application is concerned with means for guiding, floating and cementing well casing in bored holes; and it is particularly concerned with improvements in means to overcome the tendency to channel the cementing slurry through the well fluid and further to prevent the mixture of the cementing slurry with the well fluid in the well pipe during the cementing operation.

Through the use of my invention, I have minimized the hazard of permitting mud cake deposits to remain in the well bore, by providing a greater volume flow from the well casing to the well bore for wash purposes.

My invention eliminates the great expense entailed under the old practices, in that it is now unnecessary to use special pumping equipment in order to attain the required volume flow through the casing, as is done with the prior methods and devices. Through the use of my invention I eliminate the aforesaid flow restrictions in the casing, such as have been used in the prior devices.

In my invention, where it is necessary to have a restriction in the casing to perform the functions of such restrictions in the casings as have appeared in prior devices, I have provided a Venturi form of flow passageway.

By using the Venturi form of flow passage I have incorporated the following principle: When fluid flows through a venturi its velocity rapidly increases from its entrance to the throat of the venturi, and decreases from the throat of the venturi to its outlet. The pressure is greatest at the entrance to the venturi, and at the outlet, and is least at its throat. The pressure lost at the throat of the venturi is almost entirely regained at its outlet. Thus, by passing the fluid through a Venturi-like passage in the casing, almost the same amount of fluid will be delivered through the well conduit, without increasing the pressure on the pumping equipment. This Venturi principle of flow passageway inside a well casing, during a cementing operation, has not been used in the prior methods and devices for guiding and/or floating and/or cementing well casing in bored holes.

It is desirable that all fluids employed during a well cementing operation must be segregated from each other so far as it is possible to effect such separation.

Such segregation of fluids can only be accomplished within the well pipe. My means as disclosed herein provide for segregation of fluids throughout the full length of the pipe. My

2
means accomplishes a positive segregation between the fluids in the pipe; and no fluids pass through the segregating means, and substantially no fluids pass around them. Thus, I have, by the use of my means, eliminated the causes which generate the "cement-mud ball" mass formed in the casing in prior well cementing practice. This is of great importance.

In the use of small orifice fittings in the casing in prior devices used in cementing wells, as above described, the formation of "cement-mud balls" in the casing necessitated increased pumping pressure in order to force the mass formed by the "cement-mud balls" through the orifice-like restrictions. By eliminating the formation of the "cement-mud balls" in the casing in the use of my device, I can and do utilize the ordinary pumping equipment customarily used in well drilling practice. This results in extensive economies and much savings in equipment and costs.

By providing the means of my invention for segregating the well fluids, the wash water is discharged from the well pipe in a free state, and the cementing slurry is likewise discharged from the well pipe in an uncontaminated state. Thus, the greatest possible benefit is derived from the wash water and cementing slurry.

In prior cementing operations it has been the practice to disjoint the cementing head or surface fittings from the casing in order to inject the old style segregating means used as spacers between the fluids in the casing. The result of this practice has been that, while the surface fittings are disconnected, air is allowed to enter the casing. When this result occurs after the confining of the cementing slurry in the casing, the cementing slurry (being of greater density than the well fluid ahead of it) will displace the well fluid and a void will be left at the top of the column of slurry. When the well head fitting is replaced, air will then be trapped in the void thus formed between the plug inserted and the cementing slurry. Thus, the air will be trapped between the column of fluid below the plug and the column of fluid above the plug. When pressure is applied to the plug above this air pocket, the air, being of less density and viscosity than the cementing slurry ahead of it, will be compressed and will permeate into the cementing slurry and cause the formation of pockets or honeycomb-like recesses within the slurry, and thus weaken it. This is a most undesirable result fraught with grave consequences.

By the use of my device, I have overcome the

introduction of air into the bore of the well pipe by inducting all segregating means, desired for use in a cementing operation, into the casing, under pressure, while the pump is in operation, and thus causing no stoppage of the flow stream. No voids result.

Among the objects to be attained by my invention are those indicated in the foregoing dissertation, and also the following:

1. To provide means for the floating and guiding of a string of casing into a well bore and to the desired level for the purpose of cementing the casing in the well bore.

2. To provide disengageable means within the casing which may be dislodged by other means so as to provide substantially full casing area flow through the well pipe after the casing has been run to the desired level in the well bore.

3. To provide maximum area inside the well pipe for the flow of fluid therethrough so as to reduce the well pumping pressure required and to increase the volume of flow of fluid through the well circulating circuit.

4. To provide and make effective the segregation of all fluids in the well pipe during a cementing operation.

5. To provide valve means which move with the flow stream in the well pipe and operate to prevent the discharging of fluid from the well pipe, when desired; and such means further preventing the flowback of fluid into the well pipe after the discharge of the fluid from the well pipe has taken place.

6. To provide a rigid segregating means for segregating the fluids in the well pipe, which means has the capability of being deformed and reformed to the contour of the bore or passageway through the well pipe.

7. To provide means for inducting all segregating spacer means into the flow stream, inside the casing, while the casing is under pressure, and without interrupting the flow of fluid through the well flow circuit, during a cementing operation.

Other and further objects of my invention will become apparent upon the reading of the detailed specification which follows hereinafter.

My method and means for guiding, floating and cementing well casing in bored holes, and a suitable arrangement and construction of the parts thereof, and their operation and use, are illustrated in the accompanying drawings, which disclose a satisfactory and preferred form of my device.

It is to be understood, however, that I can practice my invention effectively and satisfactorily with various devices which incorporate and use the same, notwithstanding that such devices may be in forms and arrangements somewhat different from the structures illustrated in the accompanying drawings; and such departure from the structures delineated herein will not depart from the spirit and essential principles of my invention.

In the drawings:

Fig. I is a partially sectionalized elevation showing several levels in a typical well about to be cemented, wherein my float shoe and stall collar are carried by the casing in position in the bored hole, and wherein the cementing head is connected to the top of the casing above the earth's surface.

Fig. II is a partially sectionalized elevation of certain levels of a typical well at the time of dislodging my float assembly from the float shoe by pressure operated trip means, and wherein a

primary collapsible spacer plug is positioned in the cement head prior to its introduction into the well casing.

Fig. III is a partially sectionalized elevation of a typical well with a volume of cementing slurry confined in the casing between a primary collapsible spacer plug and a top collapsible spacer plug, which latter plug carries a check valve.

Fig. IV is a partially sectionalized elevation of a typical well wherein my cementing apparatus has been employed and wherein a volume of slurry for cementing the casing in the bored hole has been discharged from the casing into the well bore, and wherein a check valve prevents further movement of fluids in the casing.

Fig. V is a partially sectionalized elevation of my float shoe carried by and below the well pipe, and wherein the shoe assembly trip ball is shown in the well pipe near its seating position.

Fig. VI is a partially sectionalized elevation of my stall collar, connected above and below to the well casing, and of my collapsible spacer plug, and of my check valve.

Fig. VII is a partially sectionalized elevation of the upper portion of my cement head having an adapting liner positioned therein, and of my top collapsible spacer plug, and of my check valve.

In the drawings, the various parts and elements of structures employed in the practice of my invention, and in the construction and operation of devices required thereby, are indicated by numerals; and numeral 1 indicates the earth's strata; and numeral 2 identifies the bore of a well, whether it be an oil well, a gas well, a water well or other type of well. In Fig. I the well casing 3 has been guided and floated into the drilled hole to the desired depth.

In Fig. I the typical well casing 3 carries the float shoe 4, in which the float assembly 15 is positioned. A valve in the float assembly 15 is a back pressure check valve of a type such as has been heretofore used in floating and guiding well casing into bored holes. In this construction well fluid may flow downwardly through the float shoe, but the fluid is prevented from flowing back into the casing through the float shoe.

During the time that the casing is being guided into the well bore by the deflecting action of the rounded sides of the shoe guide 15a, the well pipe acquires a floating buoyancy. The buoyant ball 16 inside the float assembly 15, is floated upward from its seat 18a because the pressure of the fluid head on the outside of the casing is greater than the pressure of the fluid head on the inside of the casing. The float ball 16 is retained within the float assembly 15 by means of rests or arms 18a, which also form a seat for the ball, and such arms may be made integral with the float assembly 15.

In this float assembly 15 the valve ball 18 is caused to float during the time the casing is being guided into the well bore by reason of the fact that the specific gravity of valve ball 18 is less than the specific gravity of the well fluid. The area of the opening 18b through which fluid may be discharged during the guiding and floating period is much smaller than the area of the bore of the casing. Consequently, by applying pressure to the top of the casing, fluid can be caused to discharge through the opening 18b in jet-like fashion, since the fluid is being forced from a large area through a small area. This effect is useful during the guiding and floating period. Should the casing encounter mud bridges or other mov-

able restrictions in the well bore on its progress downward, fluid may be jetted through the opening 18b, by pump pressure from above so as to wash away the bridges or other restrictions.

A typical string of casing 3 also carries the stall collar 5, which is placed on the casing above the float shoe 4, at the desired level in the hole. The spaced relation between the stall collar 5 and the shoe 4 of course determines the amount of cementing slurry to remain within the bore of the casing after the cementing operation is completed; and in normal practice such spacing customarily will not exceed 100 feet. This spaced relation between the stall collar and the shoe is determined by the choice of the operator.

Also positioned on the string of casing 3 is a cement head 6, which is disposed at the top of the casing above the earth's surface. The cement head 6 and its appurtenant connections constitute the connecting means between the surface well pumps and the casing. By this cement head arrangement and connection, fluid may be pumped from the usual surface storage facilities, downwardly through the bore 8 of the casing, for discharge through the float shoe 4 into the bore 2 of the well, and thence be directed upwardly behind the casing 3 and returned to the said surface storage facilities. This entire flow passage-way, as above described, is commonly known as "the well flow circuit."

In this well flow circuit, a connecting fluid line 8a is caused to communicate with the cement head, and the bore of the casing by joinder to one opening of the cross T3. The cross T3 is threadedly connected to the top of the casing 3, and fitted below the standard commercial plug valve 7. The other opening 9a of cross T3 is shown in the drawings as being plugged, but such opening is adapted to receive connection with a conduit from the surface pumps if such connection be desired.

At the top of the cement head 6 is connected one end of the flexible hose 10, the other end of which flexible hose is caused to communicate with the fluid line 8a through valve 12, T13 and valve 11. Flexible hose 10 also communicates with flow line 18a which is in turn connected to the surface pumps (not shown).

By this arrangement of manifold valves connected between the surface pumps and the cementing head and casing, the flow of fluid into the casing can be directed and controlled. Thus, when valve 11 is in open position, while the commercial plug valve 7 and valve 12 on the flexible hose line are in closed position, the fluid pumped from the surface pumps is delivered to the bore of the casing without passing through the cement head. However, when valve 12 on the flexible hose line, and the commercial plug valve 7, are in open position, while valve 11 is in a closed position, the fluid pumped from the surface pumps through flow line 18a is delivered to the bore of the casing by passing through the cement head. This flow control arrangement is an important part of my invention, as will be demonstrated later in this specification.

While the assembly is positioned as shown in Fig. I, it may be desirable to wash and clean the well flow circuit, which is customary practice, before the cementing operation. This is done by manipulating the valve arrangement on the cementing head so that the well washing fluid will not pass through the cementing head during this washing period, but will flow directly into the casing.

However, before the well washing operation begins the float assembly 15 is dislodged from the float shoe 4 so that there will be no restriction in the float shoe during this operation. 5 This is done by manually dropping the float shoe trip ball 16 into the bore of the well casing before the cement head 6 is placed into position thereon. This trip ball 16, having a specific gravity greater than the well fluid, will gravitate to the bottom of the well casing bore until it reaches a closure seat 17 in the float assembly 15 of the float shoe 4.

The closure seat 17 is constructed of a tubular member having upper and lower tapered surfaces 17a and 17b respectively. The tubular member 17 is removably mounted in assembly 15 by means of threads 15a. Taper 17a provides a seat for trip ball 16. Taper 17b provides a seat for float ball 18, while the casing is being floated into the well bore to prevent backflow of fluid into the casing.

To facilitate the movement of trip ball 16 to its seating position it may be hastened in its progress to the bottom of the well casing by applying pump pressure to the casing through proper connections to the casing.

There is a plurality of shearing screws 19, passing through the wall of the tubular body 20 of the float shoe 4, and into the wall of the float assembly 15, so that assembly 15 is frangiblely mounted in the shoe. After the trip ball 16 has found lodgment on taper 17a of closure seat 17, hydraulic pressure is applied by the surface pumps to the bore of the casing to such an extent that the pressure applied to the trip ball 16 and assembly 15 will fracture the shearing screws 19 which permits the dislodgment and movement of the float assembly downwardly in the body 20 and thus causes its ejection from the shoe into the bore of the well.

Were the float assembly 15 not ejected from the float shoe 4, the flow of fluid through the well casing bore 8 would be greatly restricted, because it is obvious that the passage 18b is much smaller in cross sectional area than the bore of the casing. However, after ejecting the float assembly 15 from the float shoe in the manner above described, the area of opening within the shoe through which the fluid is permitted to flow is substantially the same as the area in the well pipe. Consequently, the volume of flow through the unrestricted casing bore after ejecting the float assembly is also greatly increased.

55 The float assembly 15 is shown as partially dislodged in Fig. II by the action of pressure applied to the trip ball 16, as above described. Float assembly 15 and tripping ball 16, being of greater specific gravity than the well fluid, will fall downwardly in the well bore after their dislodgment, as shown in Figures III and IV. Float assembly 15 and trip ball 16 are made of drillable material, which may be later drilled up, should the well drilling operation be carried to a depth beyond the initial subsurface positioning of the well pipe which is cemented.

70 The float assembly and tripping ball may be made of aluminum, magnesium, plastic or a combination of same, or other material of drillable characteristic. By the term "drillable" it is meant that these elements may be cut away by the drill bit, along with any cement or other materials around them, after the cementing job is finished. Such drilling may be necessary in 75 order to provide a free and unobstructed pas-

sageway for the guiding and floating of a subsequent well pipe that may be later cemented in a deepened well bore.

My invention, therefore, provides a well pipe bore which is free of all semi-closed flow restrictions. It provides a free and unobstructed conduit or passageway for the movement of cementing slurry or other fluids; and such passageway is substantially the same in cross sectional area as the bore of the casing.

After the well flow circuit has been wash-circulated to the satisfaction of the operator, the collapsible plug 14 is placed in the cementing head 6, as shown in Fig. II. This fluid segregating collapsible plug, and all subsequent fluid segregating collapsible plugs desired to be injected into the well casing, are positioned in the cementing head without interrupting the flow stream through the well circuit. Therefore, the introduction of such plugs does not require the releasing of the pressure of the circulating pumps.

The plugs may be positioned above the casing for introduction thereto by simply removing the hood or bonnet 21 from the cement head. The removal of the hood 21 may be accomplished by the withdrawal of steel pins 22 from the openings 23 in the tie-down arms 24.

The tie-down arms 24 are welded on the outer periphery and at opposite sides of the hood 21, by means of welds 24a. The tie-down arms 24 are so positioned that they extend below the bottom of the hood in such a way as to permit the openings 23 to align themselves with complementary steel pin openings 25 in the locking segments 26. The locking segments 26 are welded to the cement head body 27 by means of welds 26a. The tie-down arms 24 are thus pinned between the segments 26.

When the pin openings 23 in the tie-down arms and the pin openings 25 in the segments 26 are in alignment, the under surface 29 on the circumferential bottom rim of the bonnet or hood 21 is shouldered on the upper surface 30 on the circumferential top rim of the cement head body 27.

The removal of the tie-down pins 22 permits the bonnet or hood 21 of the cement head to be moved upwardly and apart from the cement head body 27. The bonnet or hood 21 may be moved upwardly by attaching a block and tackle (not shown) to the sling 28 positioned on the flexible hose 10.

After the bonnet 21 is removed the collapsible plug 14 may be placed in the cementing head and the bonnet may then be replaced, and locked in place. Of course, while this operation is taking place, the pump flow is directed through valve 11 and flow conduit 8a into the casing, and the valves 7 and 12 will be in closed position, so that fluid may not flow through the cementing head. Bleeder valve 31 is provided on the flexible hose line 10 for the purpose of releasing the pressure remaining in the cementing head 6 after the flow has been directed so as to by-pass the cementing head.

To make safe and simple the detaching and attaching of the bonnet or hood 21 to the body 27 of the cementing head, the internal bore surface 32 of bonnet 21 is made to provide an easy fit by slidably engagement with the outer wall 33 of the cement head body extension 34. In order to prevent fluid leakage between members 21 and 27, grooves 35 are provided on the inner side walls of the bonnet 21, in which grooves are placed resilient sealing rings 36. Thus, during the time

that the pump flow is directed through the cement head, leakage from the head is prevented.

Since different diameters of casing may be encountered in cementing operations, it is necessary to make provision for the adaptation of the cementing head to this situation. It is also necessary to make different diameters of collapsible plug 14 so that it will fit different diameters of casings encountered in cementing wells. In Figures I, II and VII there is shown a liner or cylinder 37 which is slidably disposed within the bore of the cement head body 27. This liner 37 may be made of any thickness or it may be dispensed with entirely. In this way a cementing head may be made of a standard proportion and single size and yet be adapted to different sizes of plugs 14 by the use of this variable thickness liner 37.

The means used for segregating fluids in my invention is the typical collapsible cementing plug 14. Plug 14a is of exactly the same construction as plug 14, and when plug 14 is described, such description will also apply to plug 14a.

This plug 14 is merely a preferred form, and may be made in a variety of shapes and sizes. This collapsible plug is made of resilient material, such as rubber, natural or synthetic, which has a yielding nature, and yet is capable of withstanding considerable abrasive action. This plug may be used to segregate any of the fluids used, or encountered, in the cementing operation, such as cementing slurry, well fluid, water or other fluids.

The typical collapsible plug 14, shown in the drawings, is substantially in the form of a spool, having flanges 38 on the outer periphery thereof which produce sealing action when these flanges are made to contact the walls of the bore of the well pipe. It has an irregular axial opening 39 which constitutes a hollow internal bore. At each end of the plug, ferrules 40 and 40a are inserted, and are retained inside of the ends of the plug by means of firmly secured wire bindings 41. The ferrules are provided with threads 42 on their inner surfaces, which threads provide attaching means for the closure member 43, extending member 44, or other members. A cork or other stopper 45 may also be inserted in the end of the ferrule.

Before injecting the plug 14 into the well casing, the opening through ferrule 40 is sealed by threaded engagement therein of closure plug 43, and the hollow bore 39 of the plug is filled with water or other non-compressible fluid. To maintain the fluid within the plug while it is positioned in the cement head, and so that no air will be trapped therein, the lower ferrule 40a is sealed with the cork or stopper 45.

The plug 14 is so constructed that it may be deformed to the contours of the casing, or passageway in the casing, through which it is forced by pressure; and it will reform itself to the contours of the casing, or other passageway, after passing through any constriction in the casing. When the plug is deformed by being forced through a constriction, the sealing cork 45, which is used to retain the fluid inside the plug, may be ejected from the plug by reason of the fluid pressure against it from inside the plug, so that the fluid inside the plug will be partially or wholly discharged therefrom. After the constriction has been passed the plug reforms itself to its original shape.

Plug 14, when confined under pressure, has

all of the attributes of a solid. It is made of resilient material, so that it may be elongated for passage through a restricted area, or it may be reduced in diameter by the ejection by pressure of fluid therefrom, to pass such restricted area. The rigidity of the plug is regained after passing the restricted area. This is so because a hydraulic suction is built up inside the plug, which suction is caused by the ejection by pressure of fluid from the plug when passing the restricted area. This hydraulic suction, acting in conjunction with the reflex action of the resilient material of which the plug is made, causes the plug to resume its original shape after passing the restriction; and in reconforming itself, liquid from the surrounding area, equal in volume to that discharged, will be drawn into the hollow space inside the plug by the force of the hydraulic suction. Thus my plug, being of substantially rigid characteristic, notwithstanding its non-rigid elements, is effective as means for substantially sealing off and separating the contents of a well conduit, or other conduit, at whatever places or intervals may be desired.

In Fig. II is shown the collapsible plug 14 in position in the cement head preparatory to being inducted into the well casing by pressure applied by the surface pumps. This primary plug, as shown in Fig. II, is used for the purpose of spacing the cementing slurry which follows it and the well fluid which precedes it. This plug 14 is placed in the cement head in the manner hereinabove described while the well is being wash-circulated.

After the well has been wash-circulated to the satisfaction of the operator, valve 11 is closed and valves 12 and 7 are opened so that the flow circuit will be directed through the cementing head 6.

The plug valve 7 has a central opening 46 through the key 48, which opening is shown in closed position in Figures I and II. When the valve key 48 is partly rotated by a wrench or other means, the valve opening 46 is caused to register with the lower opening of the valve 7, which leads into the casing, and opening 46 will then communicate with the interior of cementing head 6, wherein plug 14 is positioned.

In order to make the valve 7 easier to open, there has been provided a by-pass between the lower part of the cement body 27 and the casing below the valve 7. This by-pass arrangement consists of a small diameter pipe 49 connected with proper nipples, with a valve 50 thereon, which when opened, will allow the equalization of the pressure in cement head 6 and the casing below the valve 7. Thus, the valve 7 will be easier to open when the pressures on each side of its closed key are equalized.

After the pumping flow is directed through the cement head 6 in the manner hereinabove described, the pressure from the surface pumps is increased and plug 14 is forced through the central opening 46 in valve 7, and into the bore of the casing. The increased pressure from the pumps is necessary, because the opening 46 is of lesser diameter than the plug 14. The cork 45 may be forced out of ferrule opening 48a when plug 14 is forced through opening 46. The operator may tell when plug 14 has passed the opening 46 by the pressure drop on the surface pump.

After the plug 14 has passed the valve 7 and has proceeded into the casing, the valves 12 and 7 are closed (after opening valve 11) so that

the pumping flow will again by-pass the cement head 6. This is done in order that the bonnet 21 of cement head 6 may be removed in the manner hereinabove described for the placement therein of collapsible plug 14a, with its connecting extension 44 and check valve 51 attached thereto; and this operation is performed without interrupting the pumping operation or without removing the cement head 6 from its attached position on the casing string.

After the collapsible plug 14 has been forced by pressure into the well casing, in the manner hereinabove described, the cementing slurry or other well bonding material is pumped into the well casing through valve 11 and pipe 3a, after valves 12 and 7 are closed. This cementing slurry follows the plug 14, and plug 14 segregates the well fluid ahead of it from the cementing slurry or other bonding material which follows it.

In Fig. III the primary collapsible plug 14 is shown at the bottom of the well casing, and immediately above it in the casing is shown the cement slurry 70. The volume of slurry introduced into the well casing is determined by the operator to suit the particular needs of the cementing job to be performed.

While the cementing slurry 70 is being pumped into the well casing the hood 21 on the cement head 6 is removed and collapsible plug 14a is inserted into the cement head in the same manner that collapsible plug 14 was inserted therein. Plug 14a is exactly the same in construction as plug 14. Attached to the top of collapsible plug 14a is the check valve 51. The plug 14a and check valve 51 are connected by means of the extension member 44. Extension member 44 is a rod which has threads on each end thereof so that it can be screwed into the check valve 51 by means of threads 71 in the lower end thereof, and the other end of the extension rod 44 can be screwed into the threads 42 on the inside of the ferrule 40 in the upper end of collapsible plug 14a.

When the desired amount of cementing slurry has been pumped into the well casing, valve 11 is closed, after opening valves 12 and 7, so that the pump flow will be again directed through the cement head 6. Pressure is applied to the plug 14a so that it is forced through the opening 46 of valve 7 in the same manner that plug 14 was forced therethrough. The valve 51, being of less diameter than the opening 46, will follow the plug 14a through the opening 46. The plug 14a then segregates the cementing slurry 70 from the well fluid, or other fluid, which follows the plug 14a in the bore of the well casing.

After the plug 14a and check valve 51 have entered the casing, valve 11 is opened and valves 12 and 7 are closed so that the pumping flow will again by-pass the cement head 6.

Any number of spacer plugs may be injected into the well casing to segregate any number or any kinds of fluids, as may be required or desired, in the manner hereinabove described. These spacer plugs may be injected into the well casing without stopping the pumps and without interrupting the flow through the well circuit.

In Fig. III the plug 14 is shown at the bottom of the casing after valve assembly 15 of float shoe 4 has been ejected therefrom. Immediately above the plug 14 is the cementing slurry, and immediately above the cementing slurry is the collapsible plug 14a with check valve 51 attached thereto.

As the pressure flow is continued from the

11

surface pumps, and the fluids continue to flow in the well circuit, the plug 14 will be ejected from the bottom of the casing, as shown in Fig. IV, thus allowing the discharge of the slurry from the casing into the well bore.

As plug 14a progresses downwardly in the casing it will be pressure-collapsed through the stall collar 5 and will reconform itself to the walls of the casing bore below the stall collar 5. Check valve 51, being attached to the collapsible plug 14a, will be forced to stopped position in the stall collar 5, thus building up pressure on the surface pumps and preventing the further flow of fluids within the well circuit.

Fig. VI shows the check valve 51 in locked position in the stall collar with the collapsible plug 14a having passed the stall collar and conformed itself to the contours of the casing 3.

As shown in detail in Fig. VI, my stall collar 5 has a truncated inlet 52 and also has a truncated outlet 53 which inlet and outlet are joined at their smallest diameters by throat 54. This construction, as shown, forms a Venturi-like passage through the stall collar. The upper truncated inlet 52 also provides a seat and stop for the check valve 51. The check valve 51 has a taper 52a near its upper end, which taper 52a mates with seat 52.

A groove 55 is recessed into the inner surface of the truncated outlet 53, which groove extends downwardly with the vertical axis of the stall collar 5 from the smallest diameter of the said truncated outlet 53, and a top shoulder 55a is thus provided at the top of this recess 55. This Venturi-like flow passage is constructed of a cylindrical tube 56, which tube is detachably engaged with the outer body 57 by means of threads 58, which are made secure to complementary body threads 59.

The inner wall 60 of the body 57 has a greater interior diameter below the threads 59 on body 57, which construction is so provided to permit an extremely easy and slidably fit, when screwing the tube 56 to body 57, in assembling the stall collar 5.

At the lowermost point on the rim of tube 56 there is provided horizontal plane surface 61 to shoulder on a complementary horizontal plane surface 62, provided on the top rim of the stall collar extension nipple 63.

The extension nipple 63 is connected by male threads 64 to lower female threads 65 on the body 57. The bearing provided by the shoulders 61 and 62 is so constructed that the greatest possible support will be supplied to the tube 56 after it is mounted within the body 57. To further strengthen this support, extension nipple 63 is integrally attached by a suitable weld 66 to the lowermost point of the body 57. The extension nipple 63 has a male lower thread 67 for attachment to a complementary thread 68 within a coupling of the well casing string 3. It is to be noted that the bore 69 of the extension nipple 63 has the same diameter as the bore of the casing string 3, on which the stall collar is positioned.

As the collapsible plug 14a progresses downward with the flow stream inside of the well casing, by reason of pressure applied by the surface pumps from above, it reaches the Venturi-like passage inside of the stall collar 5, and the pressure from the pumps deforms it and forces it through the throat 54 in the stall collar.

The operator will know when the check valve 51 reaches the stall collar by the sharp pressure rise on his pumps. When check valve 51 reaches

12

its seating position in the stall collar, it will be forced into locked position.

The check valve 51 is so constructed that the top thereof is tapered in such a way as to seat on the truncated inlet 52 of the stall collar tube 56. It is made of some drillable material, preferably of aluminum, and is rigid enough that it will not be forced through the stall collar in the manner that collapsible plug 14a is forced therethrough.

On the lower end of check valve 51 there is an expansible split ring 72, which is contracted when the lower end of the check valve 51 is forced by pressure through the throat 54 of stall collar tube 56. When the split ring passes the shoulder 55a it will relax and snap into locking position in the groove 55. On the outer wall of the check valve 51 are sealing rings 73, which are for the purpose of preventing leakage of fluids around said check valve 51 after it has been locked in position.

When the check valve 51 is in locked position in the stall collar, it cannot be forced downward because the top thereof is firmly seated in the upper part of the stall collar tube 56, and it is prevented from moving upward because it is locked in position by the split ring 72 underneath the shoulder 55a.

When the check valve 51 is in such locked position, the surface pumps will be stalled, and the flow in the well circuit will be immediately stopped. Fluid is prevented from flowing back into the well casing through the stall collar when the pressure is released from the surface pumps, because the check valve 51 is prevented from moving upward by reason of its being locked in place by the split ring 72. Thus, there is provided an immediate shut-off of fluid being discharged from the well casing, and an immediate shut-off of fluid flowing back into the well casing. All fluid is then static.

The stall collar tube 56, the check valve 51 and extension member 44 are preferably made of a drillable material, such as aluminum, so that after the cement is set around the casing, these elements may be drilled out, for the purpose of producing oil through the casing, and also for the purpose of deepening the bore of the well, if so desired. Of course, the collapsible plugs 14 and 14a, being made of rubber or other resilient material may be drilled out also.

When check valve 51 reaches the truncated opening 52, it is necessary to increase the pump pressure in order to force it into locked and seated position in the stall collar. This increased pressure, however, is not applied to any collapsible spacer plugs used in my method, because the pressure is absorbed by the check valve 51 and stall tube 56. The members 51 and 56 in effect constitute a baffle to absorb the pressure from the pumps. This is important because the increased pressure, if applied to the collapsible plugs, would cause their distortion and allow leakage around them, with the result that there would be some mixing of fluids segregated by the plugs. My device prevents such leakage and mixing.

In the function, operation and practice of my invention the string of casing is progressively made up as it is guided and floated into the well bore. The float shoe 4, with the valve assembly 15 mounted therein, is first mounted on the lower end of the first joint of casing. Then the stall collar 5 is placed in position between the first joint of casing and the string of casing above it. This stall collar 5 may be placed at any interval along the casing as desired by the operator; but

in practice it is desirable to space it a short distance above the float shoe 4.

After the casing, with its appurtenant float shoe and stall collar, has been guided and floated into the hole to the proper depth, the trip ball 16 is dropped into the casing and allowed to gravitate toward the bottom thereof. Trip ball 16 is small enough to pass the throat 54 of the stall collar 5, but it will come to rest on the shoulder 17 in the float shoe 4.

After this operation, the cement head 6, which has already been assembled, with flexible hose 19 attached thereto, is placed in position at the top of the casing 3 by means of a suitable casing connecting collar 3a. The flow line 13a, leading from the surface pumps is connected to the flow T13, and then the cementing assembly is ready for operation.

The first step in cementing the casing in the well is to wash-circulate the hole. In order to have a full and unrestricted flow of fluids through the well flow circuit during this wash-circulating period, it is desirable to eject the valve assembly 15 from the float shoe 4 before this operation begins. The trip ball 16 has already come to rest on the taper or shoulder 17, and when pressure is applied from the surface pumps through valve 11 and flow line 2a and thence through the casing 3, to the trip ball 16, the pressure will cause shear screws 19 to be sheared off, and then the valve assembly 15 will be ejected from the float shoe body 20 into the bore of the well, as shown in Figures II, III and IV. There will then be an unrestricted passage through the casing bore for the circulation of fluid through the well flow circuit.

After the well has been wash-circulated to the satisfaction of the operator, a collapsible plug 14 is put into the casing under pressure by directing the well flow circuit through the cement head 6 by opening valves 12 and 7 and closing valve 11. Prior to this operation the collapsible plug 14 has been positioned in the cement head 6 by removing the bonnet 21 from the cement head 6, placing the plug 14 in the head as shown in Figure II, and then replacing the bonnet 21. This was done without interrupting the flow in the well circuit, because during this operation the flow has been directed through valve 11 and flow line 3a into the casing while valves 12 and 7 were closed.

After the collapsible plug 14 has been forced by pressure through the opening 46 of valve 7 and has proceeded into the casing below the cement head 6, then valves 12 and 7 are closed and valve 11 is opened so that the flow is again directed in such a way as to by-pass the cement head 6. Without interrupting the continuity of flow the cementing slurry 70 is pumped into the well casing behind the collapsible plug 14.

While the cementing slurry is being run into the well casing, bonnet 21 on the cement head 6, is again removed and the collapsible plug 14a with check valve 51 attached thereto is positioned in the cement head 6, in the manner shown in Fig. VII. The bonnet 21 is replaced and, after a sufficient amount of cementing slurry has been run into the well casing, valve 11 is closed after valves 12 and 7 are opened, so that the flow will again be directed through the cement head 6, and pressure from the surface pumps is applied to the collapsible plug 14a.

Collapsible plug 14a, carrying the check valve 51, is forced by pressure through valve 7 and into the casing in the same manner that plug 14

was introduced into the casing. After plug 14a and check valve 51 have entered the casing, the flow is again directed through valve 11 and flow line 8a into the casing, and the cement head 6 is bypassed by closing valves 12 and 7.

The pumping is continued and plug 14a, carrying check valve 51, is forced through the casing with the well fluid. Plug 14a acts as a spacer between cementing slurry 70 and the well fluid behind plug 14a, in the manner shown in Fig. III, wherein plug 14a is shown during the time it is progressing downward in the casing, and plug 14 is at the lower end of the casing but not yet ejected.

As the flow continues on its path from the surface storage facilities through the pumps, through the casing, into the well bore, and upward around the casing and back to the surface storage facilities, the plug 14 will be ejected from the bottom of the casing and the cementing slurry 70 will be discharged into the well bore as shown in Fig. IV. The plug 14a is forced by pressure through the Venturi-like restriction inside of the stall collar 5, and valve 51 is forced into seating position in the stall collar 5, in the manner shown in detail in Fig. VI, and as has been described in detail hereinabove.

When valve 51 is locked in position, it will cause the surface pumps to stall and the operator will immediately know that the cementing job has been completed, and he will stop the pumps and release the pressure thereupon. The valve 51 is locked by means of locking ring 72 so that it may not be forced upwardly in the casing by the fluid head pressure of the cementing slurry outside of the casing, and will not allow the cementing slurry to flow back into the casing above the stall collar. Thus, there is an immediate and automatic stoppage of the flow of fluid in the well circuit, in both directions, when valve 51 is brought into locked and seated position.

The collapsible spacer plug 14 may be used for the segregation of any type or kind or number of fluids used during a cementing operation; and as many of the plugs may be inserted into the well, in the manner hereinabove described, as may suit the convenience and desires of the operator.

After the cementing job has been completed, and the cement has set, the valve 51, connecting member 44, stall collar tube 55, plug 14 and plug 14a may be drilled out, in order to make the bore of the casing free of obstructions for the winning of production therethrough.

It is to be emphasized that the procedure outlined above for the practice of my invention is a continuous and uninterrupted operation. At no time during the cementing operation is the pressure released from the pumps until the cementing job is completed. During this procedure restrictions are removed from the well casing and there is provided a free, continuous and unrestricted flow of fluids through the well casing to the greatest extent possible.

Various changes and adaptations may be made in the practice of my invention without departing therefrom. For instance, the central opening through the removable assembly 15, in float shoe 4, may be permanently closed by a plate, replacing the valve seating element 17, which plate may be threaded or welded in place, across said opening. In this way trip ball 16 may be dispensed with, and pressure applied di-

rectly to the plate to eject assembly 15 from the shoe.

Also, the float assembly valve may be provided with a plurality of valve seats to accommodate a plurality of float balls, thus to make multiple check valves in this assembly when desired.

My invention as disclosed herein is primarily intended for the cementing of a string of casing at the lower end thereof. However, it is to be understood that my invention, and the method thereof, and the practice thereunder, may be used as the lower stage cementing step of a multi-stage cementing operation.

By multi-stage cementing it is meant that provision is made for the discharging of cementing slurry into the well bore in divided batches and at selected elevations or levels along the well pipe. A typical multi-stage cementing operation is disclosed in my co-pending application, Serial No. 690,969; and the present invention may be used with the system shown in said co-pending application.

To use the invention disclosed herein in a multi-stage cementing job, my stall collar and check valve unit would be eliminated and the float shoe only is used, which float shoe would be positioned for its customary function at the lower extremity of the well pipe. On the well pipe above the shoe, the multi-stage collar or collars would be positioned at the proper points.

The continuous flow and uninterrupted pumping, as is made possible by the instant invention, and the provision for the positive segregation of fluids during the cementing operation, and the elimination of flow restrictions in the well casing, are particularly adapted for use in multi-stage cementing because it is desirable in such multi-stage cementing to segregate the various quantities of fluids used in the cementing operation and that there be continuous and unrestricted flow through the well pipe during the operation.

When the terms "cementing slurry" or "slurry" are used herein, the terms are meant to include any fluid of a cementitious nature used to bond well pipe in a bored hole, whether it be plastic, cement or other materials.

From the foregoing it is apparent that I have invented an apparatus for guiding, floating and cementing well casing in the bore of a well wherein full and unrestricted flow of fluids through the well casing is attained; there is continuous flow of fluid through the well flow circuit; as many and different kinds of fluids as may be desired in the cementing operation are segregated without stopping the flow of fluids through the well flow circuit, and without releasing the pressure from the well casing; a positive and immediate closure of communication between the well casing and the bore of the well is attained by pressure, but which pressure is not applied to the fluid segregating media; with the result that the causes of costly cementing failures in the past have been eliminated, and a safe, speedy, positive and entirely dependable system introduced into the well cementing art.

I claim:

1. In a device for cementing well casing in the bore of a well, a collapsible plug made of resilient material having a circumferential surface on the outer periphery thereof engageable with the inner wall of the well casing when the plug is in normal undefomed condition, said plug having a hollow internal bore and being provided with an opening in each end thereof communicating with said bore, which openings are adapted

75

to receive closure members; a non-compressible fluid occupying said hollow internal bore; closure members initially disposed in said openings so as to confine said fluid, one of which closure members is adapted to be expelled from its opening whenever the plug is initially materially deformed by pressure applied thereto, whereby, some fluid may be expelled from the internal bore of said plug and some fluid may be drawn back into said bore when the plug assumes its original shape.

2. In a device for guiding, floating and cementing well casing in a bored hole, a tubular body adapted to form a part of a well casing string; a detachable tubular member mounted within the body, said tubular member being substantially Venturi-shaped, and having a recess at its lower end adapted to receive a relaxed split ring, and having a valve seat at its upper end; a valve head arranged to enter said member and rest on said seat to effect a valve closing the passage through the member; and a split ring carried by said head and arranged to expand into said recess and lock the valve in closed position.

3. In a device for guiding, floating and cementing well casing in a bored hole, in combination, a valve member comprising an elongated cylindrical body having a taper at the upper end thereof; a split ring on the lower end thereof; a resilient collapsible spacer plug having a plurality of flanges on the outer periphery thereof and a hollow internal bore, and threaded openings in the ends thereof; and an elongated connector member adapted to join the body member with the collapsible plug by screwing one end thereof into the bottom of the body member and the other end thereof into one end of the collapsible plug.

4. In a device for guiding, floating and cementing well casing in a bored hole, a tubular member having a tapered seat in its upper part and a shoulder in its lower part, said member being arranged for incorporation within a string of casing; a valve member comprising an elongated cylindrical body having a taper at the upper end thereof adapted to mate with said tapered seat and thus provide closure of the well casing; a split ring arranged on the lower end of said body and adapted to relax underneath said shoulder at the time of closure of the well casing, and thus prevent the body from moving upwardly in the casing.

5. In a device for guiding, floating and cementing well casing in a bored hole; a string of casing; a float shoe carried on the lower end of said casing; a float valve assembly frangibly mounted in said float shoe and adapted to be ejected therefrom by pressure; a stall collar disposed on said string of casing in spaced relation with said shoe, the interior of said stall collar being adapted to receive and lock in place a check valve to stop the flow of fluids through said casing string; a check valve adapted to seat and be locked in place inside said stall collar by pressure applied thereto; a plurality of collapsible spacer plugs adapted to provide segregation between the fluids used in cementing the well casing in the bored hole, and adapted to move with the fluid inside the casing; a plug valve; a valved conduit; a cementing head having a removable hood thereon, said cementing head being adapted to communicate with the well casing through the plug valve and with fluid circulating pumps through

75 the valved conduit; whereby said collapsible

spacer plugs may be injected into the well casing without releasing the pressure from the fluids in the casing and without removing the cementing head assembly from the top of the casing; and means for admitting fluid under pressure into the well casing and around it.

6. In a device for guiding, floating and cementing a well casing in a bored hole, a resilient collapsible spacer plug having a hollow internal bore and being provided with an opening at each end thereof communicating with said bore and having a circumferential surface on the outer periphery thereof engageable with the inner wall of the well casing when the plug is in normal undeformed condition; and insertable members closing said openings, one of which members is expellable by pressure of liquid contained in the plug when the plug is initially deformed.

7. In a device for cementing well casing in the bore of a well, a collapsible plug made of resilient material, said plug having a hollow internal bore and being provided with an opening at each end thereof communicating with said bore and having a circumferential surface on the outer periphery thereof engageable with the inner wall of the well casing when the plug is in normal undeformed condition; and a closure member inserted in each such opening.

8. In a device for cementing well casing in the bore of a well, a collapsible plug made of resilient material, said plug having a hollow internal bore and being provided with an opening at each end thereof communicating with said bore and having a circumferential surface on the outer periphery thereof engageable with the inner wall of the well casing when the plug is in normal undeformed condition; a closure member insertable in one of said openings and adapted to be expelled by pressure of liquid contained within the plug when the plug is initially deformed; a closure member removably affixed in the opening at the other end of said plug, said closure member providing a connector between said plug and a device to be conveyed thereby through a conduit.

9. In a device for guiding, floating and cementing well casing in a bored hole, a tubular body adapted to form a part of a well casing

string; a tubular member mounted within the body, said tubular member having a recess at its lower end and adapted to receive spring actuated retainer means, and having a valve seat at its upper end; an imperforate valve head arranged to enter said member by hydraulic pressure and rest on said seat to effect a valve closing the passage through the member against the flow of fluid in either direction; and spring actuated retainer means carried by said head and arranged to expand into said recess and lock the valve in closed position.

10. In a device for guiding, floating and cementing well casing in a bored hole, a tubular body adapted to form a part of a well casing string; a tubular member mounted within the body, said tubular member having a recess at its lower end adapted to receive a relaxed split ring, and having a valve seat at its upper end; an imperforate valve head arranged to enter said member by hydraulic pressure and rest on said seat to effect a valve closing the passage through the member against the flow of fluid in either direction; and a split ring carried by said head and arranged to expand into said recess and lock the valve in closed position.

SYLVESTER B. SCHNITTER.
